UNITED STATES PATENT OFFICE.

HENRY C. KARLSON, OF HASBROUCK HEIGHTS, NEW JERSEY, ASSIGNOR TO V. VIVAUDOU, INC., OF NEW YORK, N. Y., A CORPORATION OF DELAWARE.

VANITY CASE.

Application filed May 1, 1924, Serial No. 710,294. Renewed November 16, 1925.

- The present invention has reference to devices for distributing powders, and it relates more especially to a container which is insertible into a portable casing.
- 5 The main object of the invention is the production of an improved device of the character described, capable of remaining tight under ordinary handling, but which upon pressure being applied to a closure element thereof, will permit a certain quantity of powder to pass out against an overlying powder-puff, without coming into contact with the fingers of the person manipulating the latter.
- 10 A further object is to provide a device of the class aforesaid, wherein the reaction from a spring urged closure is transferred through a separate guide element therefor, uniformly to and around the edge of a primary member away from its upper face.
- 15 Another object is the provision in a device of the type specified, of a closure supported in a floating manner beneath a yielding seat so as to have a limited free movement while in contact therewith.
- 20 A still further object is to produce a device of the nature set forth in which means for retaining the aforementioned yieldable seat in its assigned position also afford supports for a resilient medium urging the closure against said seat.
- 25 Still another object resides in producing a device of the kind referred to, having releasable means for holding the closure open at option.
- 30 An additional object consists in providing a device of the species mentioned so arranged that the closure thereof may be unseated at will, while a surrounding receptacle remains in shut condition.
- 35 A general object is to furnish a practical device of the genus alluded to, composed of a minimum number of simple parts, of light but strong and durable construction, not liable to get out of working order; convenient and reliable in operation; readily taken apart for charging with powder; and amenable as well to low cost of manufacture.
- 40 Other objects and advantages of the invention will become apparent as the specification proceeds.
- With the aforesaid objects in view, the invention consists of the novel combinations and arrangements of parts hereinafter described in their preferred embodiments, 55 pointed out in the subjoined claims, and illustrated on the annexed drawing, wherein like parts are designated by the same reference characters throughout the several views.
- 60 Similar devices for the same purpose hitherto proposed have been deemed rather unsatisfactory, because they seemingly did not find a ready market. The reason therefor no doubt was that the structures employed would not keep tight but permitted leakage of powder. To a great extent this depended upon the defect that either too wide seats or valves were used, and often times the latter projected beyond their seats. 65 The faulty construction here indicated enabled the powder to lodge between a valve and its seat, or to build up at one side thereof. But, the powder which thus became packed would, when the receptacle was carried about, gradually shake loose and be spilled. Besides, the protruding part of a valve was obviously exposed to frequent knocks, causing a slight unseating thereof, which allowed the powder to seep out. The 70 several disadvantages above mentioned and resulting from the constructions referred to, are overcome by the present invention.
- 75 Succinctly outlined, the device under consideration includes in its organization a pair of dished members placed in opposed relation one inside of the other, forming together a container for powder and adapted for insertion conjointly into a vanity box. The upper one of these members is provided 80 in its top part with an exit for the powder, and from this exit or distributing opening leads a gradually sloping funnel-shaped approach. Against the underside of the aforesaid approach is lodged a gasket of pliable 85 material, projecting with its inner edge inwardly beyond that of the exit, constituting a yielding seat for a valve or closure element having its outer edge which is curved, in apposition thereto. The seat gasket is 90 maintained in place, in juxtaposition to the lower side of the approach by a follower,
- 95 100

the outer rim whereof is suitably secured to the upper container member adjacent to its top part. From the interior edge of this follower depend, spaced apart hangers, serving to guide laterally the valve element. These hangers have formed therewith, inwardly projecting foot portions affording anchorages for the extremities of a resilient medium capable of urging the valve upwardly against the seat wherewith it coacts. The before mentioned medium consists preferably of a spider spring having oppositely directed arms disposed in axially offset arrangement. Those of the arms which are situated at a higher level, contact with the closure element, while the lower arms of the spider are carried on the aforesigned foot portions in a manner to permit relative movement therebetween, although preventing them from becoming disassociated. If desired, the foot-portions before alluded to, may be extended radially inward until they merge together, the junction thereof being provided with an aperture the contour whereof comprises an annular ledge. Co-operating with this engagement means is a pendant catch affixed to the underface of the valve element. At such times as the latter is depressed a predetermined amount, the engaging catch will lock with the ledge above referred to, holding the valve open until pressure is brought to bear eccentrically at a certain place thereon, when the same becomes disengaged and resumes its closed position. A clearance opening is preferably formed in the middle part of the spring spider for the free passage of the catch therethru. For the purpose of enabling the valve element to be depressed so that the powder can be ejected by way of the exit, while an encompassing vanity box remains closed, the bottom of the latter is provided with an orifice through which the fingers of the operator may be inserted to push upwardly against the lower container member. A powder-puff usually overlying the valve and interposed between the same and the inside of the cover of the box, produces a reaction when squeezed intermediate the last-mentioned parts, which tends to open the valve element sufficiently for the powder to issue past its seat. In order to prevent leakage of the powder through the orifice, a supplementary bottom is introduced beneath the underside of the lower container member and the internal face of the bottom of the vanity box, being fastened at its periphery to the latter. The false bottom spoken of, consists preferably of an annularly corrugated diaphragm admitting of upward distortion without taking a permanent set.

The advantages of the invention as here outlined are best realized when all of its features and instrumentalities are combined in

the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted merely as showing the preferred exemplification of the invention.

In the said drawing:—

Figure I is a sectional elevation of this improved powder distributing device, combined with a vanity box, shown on an enlarged scale, rearwardly located parts being omitted for the sake of clearness;

Fig. II is a sectional plan view, taken irregularly on the line II—II of the preceding figure, looking downwardly thereon;

Fig. III is a fragmentary side elevation of a part of Fig. I;

Fig. IV is a transverse section taken on the line IV—IV of Fig. II, viewed in the direction of the thereto appertaining arrows; and

Fig. V is a fragmentary plan view, taken on the line V—V of Fig. I, looking in the direction pointed out by the arrows.

Referring now to the several views of the annexed drawings, for a detailed description of the invention, it will be noted that capital letters are employed to designate the known parts of the vanity box, and the same as used herein, are meant to indicate as well other existing structures to which this improved device is applicable, that is, such entities as are not deemed to pertain to the present improvements, except in so far as they form therewith legitimate combinations of elements capable of yielding novel and useful results. On the other hand, the elements and members identified with said improvements, are denoted by reference numerals in the approved manner.

Pursuant therefore, to the mode of notation herein adopted, A represents the outer upstanding side or wall of a vanity box of well known construction, B the bottom of the same, and C a slightly contracted neck adjoining the side wall near the top thereof. Taking over this neck is a cover D connected to the wall A in any convenient manner. Inside of the flange usually surrounding the before mentioned cover, is a mirror E, held in place by a ring F, in accordance with prevailing practice.

Removably inserted within the vanity box above referred to, is a container composed of upper and lower members 11, 12 respectively. These members, as shown, are of shallow cup or dish formation, being disposed in inverted and converted relation one inside of the other. The lower con-

tainer member which preferably is snugly fitted to the interior of the upper and outer one, serves as a recipient for loose face or complexion powder placed therein.

- 5 With the object in view of facilitating separation of the said members 11, 12, one from the other, the top and bottom corners thereof may be provided with circumferential beadings 13, 14, respectively. And, 10 in addition thereto, the outer wall of the upper member can be supplied with cut-outs or notches 15 in the opposite side thereof, to increase the grip of the operator's fingers when taking the members apart.
- 15 The upper one of the said container members has a head or top part 18 furnished with a centrally depressed exit or opening 19 through which the powder to be distributed issues. An upwardly outward flaring or frusto-conical approach 20 leads 20 from the edge of this distributing opening to a point situated inwardly of the corner beading 13.

Associated with the underside of the said approach 20 is a gasket 22 of rubber or other pliable material, the inner edge 23 whereof reaches inwardly beyond that of the exit 19, constituting a yielding seat for the curved rim 25 of a valve or closure element 26. This valve is preferably of convexo-concave type, having its highest point below the head 18. The means for retaining the seat gasket 22 in its assigned place, juxtaposed to the lower face of the approach 20, consists preferably of a follower 27, having a border or flange 28 received in the groove forming the interior of the before-mentioned top corner beading 13. One way of entering the flange 28 into this groove, 40 is represented at the right hand side of Fig. I, wherein it is indicated that a substantially annular crimp 30 momentarily formed in the said flange reduces the width thereof sufficiently to enable the follower 27 in its entirety, to pass within the wall (11) of the upper member. Subsequent to placing the flange 28 in juxtaposition with the inner face of the head 18, the said crimp 30 is flattened, which causes the said flange 28 45 to stretch or expand until the edge thereof fills the interior of the beading 13, becoming firmly secured therein. It will be observed that intermediate the follower proper 27, and its flange or border is formed a shoulder 32, against which as an abutment, is lodged the outer edge of the gasket 22.

The free or inner margin 34 of the said follower, which by preference is set outwardly away from the corresponding edge 50 of the seat 23, so as to increase the flexibility thereof, has depending therefrom circumferentially spaced legs or hangers 35 constituting a guide cage for the valve element 26. The latter is afforded a limited 55 lateral movement within this cage beneath

the seat wherewith it coacts. The benefit derived from such an arrangement, taken in conjunction with a narrow contact between the seat and the valve, is that the latter in finding a bearing against the former, 70 also tends to free itself of powder which has collected thereon, instead of embedding the same between meeting surfaces of comparatively large area. The employment of a yielding seat possesses the advantage that 75 not only are imperfections or irregularities occurring in the faces of the valve 26 and the edge 19 of the approach 20 absorbed or compensated for, but also minute particles of powder which have become caught 80 between the narrow contacts of the soft seat and the rim of the valve, are held fast and not as liable to shake loose, as when seized intermediate two metallic surfaces, 85 at such times as the vanity case as a whole is handled or carried about.

At the lower extremities of the hangers 85, are inwardly projecting foot-portions 36, the sides whereof are provided with lugs 37 adapted to be bent over the latter, for a 90 purpose that will appear later on. A resilient medium for urging the valve element 26 towards its seat, in the exemplification shown, consists of a star-shaped spring. As represented, this spring medium comprises arms 40, 41, radiating from a middle part 43, which is centrally provided with an opening 44, the object whereof will be more fully hereinafter pointed out. As will be observed with particular reference to Figs. 95 I and II, of the annexed drawing, the before-named arms are offset in groups of preferably not less than three, at different planes relatively to one another, in opposite directions from the said middle part 43. Those 100 of the arms (41) that are disposed at a higher level, bear at several places with their free ends against the underside of the valve 26, near the rim thereof, while the lower arm 40, which have formed therewith enlargements 46, at their outer extremities, 105 are supported on the above mentioned foot-portions 36. From the foregoing it will be seen that the closure 26 is floating upon a plurality of yielding supports, directly engaging and in offset relation thereto. The lugs 37 pertaining to the foot-portions 36: 110 are folded over upon the arms 40, inwardly beyond their enlargements, and serve to retain the said star-spring in position on the foot-portions, while affording the lower arms a slight movement, at such times as a downward pressure is imposed upon the valve 26. By virtue of the before described 115 construction, one side or the other of this valve is compressible, in a wobbly fashion, or the entire valve may be pushed downwardly in an even manner all the way around, within the cage composed of the hangers 35, depending both on the amount 120 125

of powder to be educed from the lower container member, and upon the quantity stored therein.

As indicated at 48, the foot-portion 36 may be extended in an inward direction, until they meet as at 49, their said junction being provided with an aperture 50, which is smaller in diameter than the opening 44 through the central part 43 of the star-spring, but concentric therewith. The lower edge of the aforesaid aperture 50 constitutes an annular ledge with which is adapted to cooperate, the upper face at one side of a head 52 formed at the lower terminal 19 of a stud 53. This stud and head constitute a pendant catch affixed to the underside of the closure element 26 and disposed eccentrically with relation thereto. By reason of the last mentioned arrangement, the head 20 52 is capable of taking under the aperture ledge 50 irrespective of their interrelative circumferential positions, providing that the said element 26 is depressed sufficiently deep, for the before named engagement and 25 engaging means to come into coaction. During normal actuation of the valve element, to educe an ordinary supply of powder for a facial application, the said valve is not pushed down far enough to effect the 30 engagement referred to. But, at such times as it is required to fill or charge the container proper, without removing it from the vanity box, then the valve 26 is forced down until the head of the catch slips by and becomes locked with the lower edge of the 35 aperture 50. When it is desired to disengage the above named locking or detent means, pressure is brought to bear upon the said valve element farther away from the 40 center of the latter, than where the catch is located, but on a radial line therewith. This will swing the catch off its ledge. For the purpose of denoting to the operator where to place the finger in order to perform the disengaging act, a small protuberance 55, may be struck-up from the valve's top face. A slight tap by the finger on this raised spot is generally sufficient to free the valve, which then under the influence of its 50 spring snaps back towards the seat 23.

Interposed between the valve element 26 and the downwardly turned face of the mirror E, is a powder-puff, shown by dot and dash lines at G. With the object in view of causing the said valve to open so that powder may be shaken out of the exit covered thereby, against the lower face of the powder-puff, while the encompassing vanity box remains closed, the bottom of the latter is 55 provided with a rimmed orifice 57. Through this orifice the operator is enabled to insert a finger and press upwardly on the underside of the container, contemporaneously with the other fingers of the hand 60

grasping over the cover of the vanity box, 65 to maintain the former shut while shaking or vibrating the latter. The upward pressure of the finger through the orifice 57, acts to raise the container bodily, until its closure element 26 is forced sufficiently hard 70 into contact with the overlying powder-puff to cause the reaction therefrom to depress this element, when obviously small amounts of powder can find their way out, upon agitation of the vanity box in its entirety. 75

In order to prevent powder from escaping by way of the said orifice, a diaphragm 59 is laid thereover upon the inside of the bottom B of the vanity box, being secured by its edges 60 to the adjacent corners of the upstanding walls A of the box. The before named diaphragm is preferably formed with annular corrugations, so as to enable it to partake of considerable distortion without receiving a permanent set therethru. Axial 85 movement applied by the operator's finger to the said diaphragm, interposed as represented in Fig. I, intermediate the bottoms of the vanity box and that of the lower container member, is transmitted to the latter. 90

The mode of operation of the device will be understood from and has been given in substance with the description of the parts above recited. Suffice it to say that there is nothing to get out of order, and no 95 ground-in surfaces to be kept tight. The powder is free to flow around the supporting structures for the valve as also underneath the latter without impeding movement imparted thereto. It is clearly seen, that the lower container member can be omitted, by snugly fitting the upper one thereof within the sides of the vanity case, to prevent leakage of powder therebetween. Furthermore, for low priced articles, it is feasible to omit, 100 both the means for locking the valve in open position, and the distortionable diaphragm. Moreover, it is obvious that the vanity box may be disregarded, and the interengaging 105 container members used alone, simply by 110 providing the upper member with a plain removable lid.

While a certain preferred embodiment of this device has been shown and described, it will be understood that changes in the form, arrangements, proportions, sizes and details thereof may be made, without departing from the scope of the invention as defined by the appended claims. 115

Having described my invention what I 120 desire to secure by Letters Patent and claim, is:

1. A device of the class described, comprising in combination, a member having a depressed seat, a dished approach extending upwardly outward from the latter, and an upwardly acting spring urged closure co-operating with the underside of said seat 125

and projecting thereabove, said closure being disposed below the outer limit of said member in both the open and closed positions.

2. A device of the class described, comprising in combination, a member provided at one side thereof with an opening, a valve element cooperating with the latter projecting therethru from below and terminating beneath the upper face of the member when in closed position, and yielding means intermediate said opening and said element, said means being carried from the underside of said member.

3. A device of the class described, comprising in combination, a member formed with an exit through the face thereof, a closure coacting with said exit, a yielding medium interposed between the exit and said closure, means for urging the latter and said medium into engagement one with the other, and other means for holding the medium up against the underside of said member beyond its exit.

4. A device of the character described, comprising in combination, interfitting members forming a container between them, the upper one of said members having an opening, a closure element therefor, means urging said element against said opening, a support for said means coacting with said upper member, and yielding means intervening of the edges of the opening and the element, being held in position intermediate the said member and said support.

5. A device of the class described, comprising in combination, a member having an exit, a yielding seat associated therewith, means for holding the latter in its assigned position, and a spring-urged valve cooperating with said seat to close said exit.

6. A device of the class described, comprising in combination, a member provided with an opening therein, a yielding seat projecting inwardly of said opening, a follower holding said seat against said member, and resiliently actuated valve means associated with the free edge of the said seat.

7. A device of the class described, comprising in combination, a member having an opening, a yielding seat constituting the inward continuation of said opening, a follower serving to hold said seat to said member, a valve coacting with the seat, and means urging said valve against the latter supported from said follower.

8. A device of the class described, comprising in combination, separable top and bottom members together constituting a container, beadings extending around the outer corners of said conjoined members, the lower portion of the top member being provided with opposed finger notches, the upper part of the same member having formed therein an opening, and a spring pressed

valve serving to close the latter, said valve being sustained from the top member substantially above the notches therein intermediate the beadings of both members.

9. A device of the class described, comprising in combination, a member having an exit therein, a yielding seat associated with the latter, projecting inwardly thereof, a valve coacting with the free edge of said seat, a resilient medium urging said valve thereagainst, and a support for said medium connected to said member serving to hold the outer portion of the seat thereto.

10. A device of the class described, comprising in combination, a member formed with an opening therethru, a valve coacting with said opening, a support including spaced apart hangers depending from said member, and a spring medium having plural arms bearing in opposite directions against said support and said valve urging the latter towards the said opening.

11. A device of the class described, comprising in combination, a member having a depressed opening therein, a yielding seat associated with said opening, a retainer for said seat, a valve coacting with the latter, a resilient medium urging said valve against the seat, and means depending from said retainer serving as an anchorage for said medium.

12. A device of the class described, comprising in combination, a member having an exit at one side thereof, a gasket lodged against the underside of said member with its edge extending inwardly of said exit constituting a seat, a spring pressed valve coacting with the latter, and a follower retaining said gasket in position, said follower including means crimped into engagement with the said member.

13. A device of the class described, comprising in combination, a member formed with an opening in the top thereof, the free edge of said opening being provided with a yielding seat, a spring-urged valve coacting tangentially with the underside of the latter, and means distinct from said valve guiding the same while permitting it limited lateral movement relatively to said seat, said means serving also to clamp the portion of the seat remote from said free edge to said member.

14. A device of the class described, comprising in combination, coacting members forming a container, and having an engagement part therewithin, one of said members being provided with an opening, a valve cooperating with the latter, a medium urging said valve toward said opening, and detent means adapted to engage said part in holding the valve open against the action of said medium.

15. A device of the class described, com-

prising in combination, a container insertible together with an overlying powder-puff into a vanity box below its cover, a spring urged valve closing an opening on said container beneath the powder-puff, and means disposed endwise of the box enabling the container to be shifted bodily therein to cause squeezing of the powder-puff against the closed cover to open said valve.

10 16. A vanity case comprising a container

having a member provided with an opening therein, a cage-like element connected to said member including hangers underlying said opening, a valve within said element loosely guided by said hangers, and means interposed between the element and said valve exerting pressure on the latter near its outer edges to normally hold the same seated against the said member. 15

HENRY C. KARLSON.
